UNITED STATES PATENT OFFICE.

MARY A. L. HINE AND ORRIN S. REED, OF CHICAGO, ILLINOIS.

BOTTLE-WRAPPER.

SPECIFICATION forming part of Letters Patent No. 352,188, dated November 9, 1886.

Application filed February 23, 1886. Serial No. 192,814. (No model.)

To all whom it may concern:

Be it known that we, MARY A. L. HINE and ORRIN S. REED, of Chicago, county of Cook, and State of Illinois, have invented certain new and useful Improvements in Bottle Wrappers or Envelopes, of which the following is a full, clear, and exact description, that will enable others to make and use the same, reference being had to the accompanying drawings, forming a part of this specification.

The object of this invention is to provide a wrapper or envelope for bottles and other analogous articles of a fragile nature, the purpose being to prevent breakage when packed in cases for storage or transportation.

Figure 1 is a plan view of a number of bottle-wrappers embodying our improved features, and showing their relative position when arranged in a packing-case. Fig. 2 shows a diaphragm or division-board; Fig. 3, a side elevation of the wrapper. Fig. 4 is a perspective of a projecting ring or flange adapted to encircle the wrappers. Fig. 5 is a perspective view of the lower end of a wrapper; and Figs. 6, 7, and 8 show modifications.

Referring to the drawings, A represents a bottle wrapper or envelope in the form of a cylindrical shell or tube open at both ends; B, a protecting-ring adapted to encircle the exterior surface of the wrapper, and C a diaphragm or division-board to be arranged between each series or layer of bottles in the packing-case.

The wrapper or envelope will ordinarily be composed of straw-board; but any other material that is suitable for the purpose may be employed.

This wrapper will usually be provided on the lower end with the lugs a', which are adapted to be inserted in and project through the rectangular slots a" in the division-diaphragm C. The lugs may then be bent inward in the direction of each other and flattened on the under side of the division-board, (see Fig. 3,) thus serving to secure each layer or the series of wrappers in each layer to the said board for the purpose of facilitating the handling of the contents of the package.

The ring or series of rings B—as any num-

ber may be used—are adapted to encircle the exterior surface of the cylindrical wrapper and project laterally therefrom, forming an adjustable protecting-flange, and preventing the wrappers from having contact with each other, and at the same time more surely preserving the contents of the package from harm. These rings will be made to have a close fit or bearing on the wrappers, so as to adjustably retain the position in which they are placed. Usually, however, these rings will be provided on the inner edge with the lips b b', one of which projects upward, and the second in the opposite direction, as illustrated in Fig. 4. These lips may be attached to the exterior surface of the wrapper by means of some suitable adhesive composition, thus permanently securing the rings in place. By this means the rings are also prevented from slipping off and being lost, as it is the intention to make a wrapper or envelope of such a durable nature as to permit of the same being used more than once. The rings will be arranged at intervals and alternate on adjacent or companion wrappers, so as to nest together in packing, as shown in Fig. 3. This construction and arrangement of the several parts forms a durable structure, and one that possesses sufficient elasticity to protect the contents of a package against a heavy jar or rough handling.

We do not confine or limit our improvement to the precise construction and arrangement shown, but may make such changes in detail and form as will adapt the envelope to be used on articles of a different contour other than cylindrical, as illustrated in Figs. 6, 7, and 8.

Having thus described our invention, what we claim, and desire to secure by Letters Patent, is—

1. In a bottle-wrapper, the combination, with an envelope or tube forming the wrapper proper, of a number of rings encircling the exterior surface of said wrapper, substantially as and for the purpose set forth.

2. In a bottle-wrapper, the combination, with the envelopes A, of one or more protecting-rings, B, encircling said envelopes and

arranged alternately thereon, whereby said rings overlap each other on adjacent wrappers in packing, and the removable diaphragm C, as described, and for the purpose set forth.

5 3. A bottle-wrapper consisting of a cylindrical envelope or tube, provided with lugs *a*', and the rings B, provided with the lips *b*', in combination with the diaphragm C, hav-

ing the slots *a*², substantially as and for the purpose set forth.

MARY A. L. HINE.
ORRIN S. REED.
